UNITED STATES PATENT OFFICE.

FRANCIS MEISEL, OF DORCHESTER, MASSACHUSETTS, ASSIGNOR TO MEISEL PRESS AND MANUFACTURING COMPANY, OF BOSTON, MASSACHUSETTS.

FOLDING-MACHINE.

1,186,018.

Specification of Letters Patent.

Patented June 6, 1916.

Application filed December 26, 1911, Serial No. 667,809. Renewed November 1, 1915. Serial No. 59,152.

To all whom it may concern:

Be it known that I, FRANCIS MEISEL, a citizen of the United States, residing at Dorchester, in the county of Suffolk and 5 Commonwealth of Massachusetts, have invented certain Improvements in Folding-Machines, of which the following description, in connection with the accompanying drawings, is a specification, like reference 10 characters on the drawings indicating like parts in the several figures.

This invention relates to folding mechanism and is herein illustrated in connection with a machine for forming in a web of 15 paper or similar material a series of zigzag folds.

Hitherto it has been customary to crease or perforate the web at intervals preparatory to making the folds before feeding it 20 to the folding cylinders, whereby a creasing or perforating mechanism separate from the folding cylinders was required. In order, therefore to obviate the necessity for such 25 separate mechanism, one object of the present invention consists in the provision in a machine of the class described of a pair of revoluble cylinders adapted to receive between them a continuously fed web, coöperating means carried by said cylinders for 30 creasing or perforating said web at intervals, means acting alternately for holding alternate portions of said web first upon one cylinder and then upon the other for a portion 35 of its respective revolution, and means for stripping the web from the cylinders and laying it in zigzag folds. There results, thus, a combined creasing or perforating and folding machine of compact form and 40 simple structure whereby the desired result is accomplished with great speed and efficiency.

In the illustrative machine the alternate portions of the web are held first upon one cylinder and then upon the other by means 45 of suction; and, in order to facilitate this operation and to simplify the mechanism by which it is applied, another feature of the invention consists in the provision of two stationary chambered bearing members arranged side by side and provided with peripheral channels connecting with the interior thereof, and a pair of revoluble cylinders mounted respectively upon said members, said cylinders being provided with 50 rows of ports, one row for each fold to be

produced, which register alternately with said channels whereby alternate portions of a web are carried first in one direction upon the periphery of one cylinder and then in the other direction upon the periphery of 60 the other.

These and other features of the invention, including certain details of construction and combinations of parts will be described in connection with an illustrative machine and 65 pointed out in the appended claims.

Referring now to the accompanying drawings, Figure 1 is a cross section through a folding mechanism in which the present invention is embodied. Fig. 2 is a section of 70 the chambered member and cylinder on the lines B—A, A—C of Fig. 1 looking in the directions indicated by the small arrows, the cylinder and member having been opened out to show the parts more clearly. The 75 upper half of Fig. 2 is thus a section on the line B—A, and the lower half is a section on the line A—C. Fig. 3 is a section similar to Fig. 1 but showing a modification in which a fan is located inside the 80 chambered member. Fig. 4 is a section on the line D—E of Fig. 3. Fig. 5 is a section similar to Fig. 1 but showing a second modification in which pressure is dispensed with 85 and the web is stripped from the cylinders by suitably actuated fingers, and Fig. 6 is a section on the line F—G.

Referring now more particularly to Figs. 1 and 2, the two portions of the folding mechanism are identical except for the relative position of certain channels, and consequently it will be sufficient to describe one of them in detail.

Fast to the frame 1 of the machine are two sleeves 3 and 5, and in these sleeves a 95 chambered bearing member 7 is held in fixed position by screw bolts 9. This bearing member comprises a central tubular portion having an imperforate partition 11 at its center, circular flanges 13 the peripheries of which serve as bearings for a cylinder presently to be described, and a radiating chambered portion the cross-section of which is approximately a sector as will be apparent from an inspection of Fig. 1. 100 This radiating portion is provided with a suction chamber 14 and a pressure chamber 15, the chamber 14 being connected with the bore of the tubular portion on one side of the partition 11 by a slot 17 and the cham- 110

ber 15 being similarly connected with the bore on the other side of the partition by a similar slot 19. The right-hand end of the tubular portion of the member 7, as viewed in Fig. 2, is connected with any suitable source of suction, and the left-hand end with any suitable source of pressure, the plain arrows indicating the direction of action of the suction and the feathered arrows that 10 of the pressure when ports and channels, presently to be described, are in register.

Portions of the flanges 13 form the end walls of the suction and pressure chambers; the side walls are formed by webs 21; and the outer wall is curved on the arc of a circle, as shown in Fig. 1, and connects the ends of the webs 21. A web 23 separates the suction chamber from the pressure chamber. In the periphery of this outer wall are 20 formed suction channels 25, said channels extending straight through the outer wall opposite the suction chamber 14 and being extended onto and nearly across that portion of the outer wall opposite the pressure chamber 15, as shown in full lines in the left-hand member of Fig. 1. Similar but shorter pressure channels 27 extend through the outer wall opposite the pressure chamber 15, as shown in full lines in the right-hand member of Fig. 1. The suction channels are approximately 90 degrees in length and the pressure channels approximately 45 degrees in the illustrative machine.

Mounted to revolve upon this chambered member, which has been described above, is a folding cylinder 29 having rows of suction ports 31 and similar rows of pressure ports 33. In the illustrative machine there are shown two rows of four suction and two 40 rows of four pressure ports, but it should be understood that the number of rows as well as the number of ports in each row may be varied as desired. The suction ports 31 are spaced longitudinally of the cylinder 45 so as to be in line circumferentially of the cylinder with the suction channels 25; and the pressure ports 33 are similarly spaced to be similarly in line with the pressure channels 27.

50 Any suitable means for rotating the cylinder may be provided, and, as shown, said cylinder is fast to a gear 30. The right-hand cylinder, as viewed in Fig. 1, has been described; the left-hand cylinder is similar 55 in construction, and the corresponding elements of said left-hand cylinder have been given the same reference numerals with the exponent '. It will be understood that the pressure channels of one member are arranged in line with the suction channels of the other member, that is, a transverse section through the cylinders in the plane of any two suction ports of one cylinder cuts through the two corresponding pressure 60 ports of the other cylinder. In Fig. 1, for

example, the section is through the two suction ports 31' of the left-hand cylinder, and this plane cuts through the two corresponding pressure ports 33 of the right-hand cylinder. It will now be clear that 70 when the cylinders are rotated in the directions indicated by the arrows in Fig. 1, first a row of suction ports of one cylinder will register with the suction channels from upper points just above a horizontal plane 75 through the axis of rotation of said cylinder to lower points substantially in a vertical plane through said axis; and then, after an interval, a row of pressure ports will register with the pressure channels 80 from upper points in a plane extending through said axis and inclined at approximately 45 degrees to lower points located slightly beyond the vertical plane referred to above. 85

With the construction thus far described, if a web of paper 100, creased or perforated at intervals, is properly fed to the cylinders the operation of the machine will be as follows: Starting with the parts in the positions shown in Fig. 1, the lower row of suction ports 31 of the right-hand cylinder is holding the web in place upon said cylinder. When the cylinders have revolved a few degrees, this row of ports will pass 90 the ends of the corresponding channels 25 thereby freeing the web, while at approximately the same time the row of suction ports 31' at the right of the other cylinder will have come into register with the channels 25' thereby sucking the web to the left-hand cylinder. When the cylinders have revolved approximately 45 degrees farther, the row of pressure ports 33 at the left of the right-hand cylinder will register with 95 the pressure channels 27 thereby stripping the right-hand fold from the right-hand cylinder; and, during the next 45 degrees of revolution, the air forced through these ports will lay the right-hand fold in place 100 between the rows of guide-posts 35. At the end of the latter 45 degrees of revolution the row of pressure ports 33 will pass out of register with the pressure channels 27, and the upper row of suction ports 31 105 will register with the upper ends of the suction channels 25 thereby sucking the web to the right-hand cylinder again. When the cylinders have rotated approximately 45 degrees farther the upper row of pressure 110 ports 33' will come into register with the pressure channels 27' in the left-hand cylinder and will continue to be operative for approximately 45 degrees farther when the parts will have reached a position 115 120 degrees from that shown. For all operative purposes, however, the parts will be in the identical position shown with the paper about to be drawn to the left-hand cylinder.

Zigzag folding machines in which alter- 130

nate pressure and suction is used have been known; but the use of channels and ports located and operating as described above is new and possesses the advantage that pressure is applied to one side of the web for a considerable portion of the revolution of one cylinder while suction is being applied to the other side of the web through the other cylinder; and this coöperation of the suction and pressure serves to form and lay the zigzag folds in a much more satisfactory manner than has been the case hitherto.

Ordinarily the web is creased or perforated before it is fed to the cylinders, but in the present invention this operation of creasing or perforating is accomplished by means carried by the cylinders themselves. And to this end each cylinder is provided with the following devices: Perforating or creasing blades 37 bent at a right angle and extending throughout the length of the cylinder are held in place by steel clamping members 39 which in turn may be fastened to the cylinder by any suitable means such as screws, said blades being located adjacent the pressure ports 33 and having their shanks perforated in line with said ports. The cylinder is also provided with cutting beds in the form of brass rods 41, said rods being held in place by two steel clamping pieces 43, 45 which may in turn be fastened to the cylinder by any suitable fastening means. These clamping members for the brass rods, it will be noted, are spaced so as to permit the edge of the blade to reach the rod which forms the cutting bed.

The creasing or perforating means associated with the right-hand cylinder has been described above; that of the left-hand cylinder is identical, and to the corresponding elements have been given the same reference numerals with the exponent '.

Further description of the operation of the machine is believed to be unnecessary. It should be noted, however, that the suction ports are located adjacent the cutting beds so that the paper is firmly held during the perforating operation.

Referring now to Figs. 3 and 4 the stationary chambered member 107 has an enlarged portion 108 in the form of a cylinder, the outer surface of which serves as a bearing for the folding cylinder 129. The end of the bearing cylinder is closed by the circular flange 110 of a second stationary member 112. The members 107 and 112 are in effect a single member, being held together by screw bolts 114 and being held fast in the frame 101 of the machine by screw bolts 116. There is thus produced a stationary bearing member, in the interior of which is a chamber 118 in which is located a fan having vanes 120 fastened to the webs 122 of hubs by means of screws 124 said hubs being in turn pinned to a shaft 126 as shown

in Fig. 4. This shaft has one end mounted in a bushing in the member 112 and the other end in two bushings in the member 107, and is adapted to be rotated by power applied to a driving pulley 128.

Leading from the interior to the periphery of the stationary bearing cylinder 108 are a plurality of suction channels 125. The pressure channels 127 extend part way into the shell of the bearing cylinder but not entirely through it and are connected with a pipe 132 which leads from their bases back into the chamber 108. A collar 134 pinned to the shaft 126 prevents it from becoming displaced; and a gear 130 is fast to the folding cylinder 129 and provides means for rotating said cylinder. Two rows of suction ports 131 extending lengthwise of the folding cylinder have their individual members so spaced as to be in line with the suction channels 125 with which they register at given intervals. And similarly two rows of pressure ports 133 are arranged to register with the pressure channels 127. Perforating blades 137 and cutting beds 141 are mounted upon the folding cylinders.

The right-hand portion of the mechanism, as viewed in Fig. 1, has been described. The left-hand portion is of similar construction, and to the corresponding elements have been given the same reference numerals with the exponent '.

When the fans and cylinders are revolved in the directions indicated by the arrows in Fig. 1 and a web of paper 100 is fed to said cylinders, said web will be sucked to that cylinder the suction ports of which register with its suction channels, the air being slightly compressed in the chambered member, and, as soon as the pressure ports register with the pressure channels, the web will be stripped from the cylinder. And in order to increase the force of the pressure there may be provided, if desired, a one-way spring-pressed ball valve 140 for permitting a stronger current of air to be forced through the pipe 132 and pressure ports 133.

The operation of the modification which has just been described is the same, so far as the web of paper is concerned, as that of the machine shown in Figs. 1 and 2 and will not be set forth further in detail.

Referring now to Figs. 5 and 6, in which a second modification is shown, this modification is similar in every way to that shown in Figs. 3 and 4, except that no pressure channels are provided and the web is stripped from the cylinders and laid in folds by mechanically actuated fingers. These fingers and the mechanism by which they are actuated are identical and consequently only one set of fingers and their actuating mechanism need be described.

Formed in the periphery of the folding cylinder are two sets of grooves or sockets

202 in which two rows of curved stripping fingers 204 normally lie, the fingers of each row being fast at their inner ends to an actuating rod 206, said rod being rotatably held in longitudinal grooves in the cylinders by fastening plates 208 which may be held to the cylinders in any suitable manner as by screws; or the rods may be mounted in bores in the wall of the cylinder, the essential feature being that said rods shall be capable of angular movement about their axes. In the illustrative machine the stripping fingers 204 are fast to arms 210 on the rods, said arms being capable of being received in sockets 212.

As has been stated the stripping fingers normally lie in sockets in the periphery of the cylinder in the manner indicated in the upper portion of the right-hand cylinder shown in Fig. 5. In order to cause the fingers to move outwardly about the axis of the rods 206 at the proper time, a cam member 214 having a cam way 216 is fastened to the stationary member 218 by a set screw 220. Rollers 228 rotatably mounted upon spindles 222 travel in the cam way 216, the spindles of said rollers being carried by arms 224 which are fastened to the rods 206 by set screws 226. The outline of the cam way 216 is shown in dotted lines in Fig. 5 from which it will be seen that the fingers begin their outward movement approximately a quarter revolution after the corresponding row of the suction ports 231 has passed out of register with the suction channels 225. The stripping means in the present modification thus comes into operation at approximately the same time that the corresponding stripping means do in the two previous modifications during the time that the web is being sucked into contact with the opposite cylinder.

It should be noted that the set screw 220 permits adjustment of the cam 214 so as to vary the time of actuation of the fingers 204, and that said fingers are spaced apart so as to permit them to pass the posts 233.

The operation of the machine shown in Figs. 5 and 6 will be clear from the operation of the machine shown in Figs. 1 and 2 and will not be described in detail. It will be sufficient to explain that the web 100 is alternately sucked to one or the other cylinder 229, 229' by air drawn through the channels 225, 225', and then stripped from the cylinders by the fingers 204, 204'.

Attention is directed to the fact that each embodiment of the invention comprises stationary chambered bearing members provided with peripheral channels communicating with the interior thereof, means for drawing air through said channels, folding cylinders rotatable upon said members and having rows of ports which register at intervals with said channels, coöperating creasing or perforating means carried by

said cylinders, whereby the web is creased or perforated and then carried first in one direction and then in the other to produce oppositely extending folds, and means for stripping the folds from the cylinders and laying them in zigzag form.

Although the invention has been set forth in connection with certain illustrative machines, it should be understood that the invention is not limited in the scope of its application to the particular machines shown and described.

Having thus described my invention, what I claim and desire to secure by Letters Patent of the United States is:

1. A machine of the class described having in combination a pair of revoluble cylinders adapted to receive between them a continuously fed web, said cylinders being provided with rows of suction ports adapted to seize portions of the web and carry them alternately in opposite directions, creasing or perforating beds mounted in said cylinders in close proximity and parallel to said rows of suction ports, and creasing or perforating plates also mounted in said cylinders and arranged to coöperate with said beds approximately simultaneously with the beginning of the action of the suction ports and at approximately the same location on the web.

2. A machine of the class described having in combination a pair of revoluble cylinders adapted to receive between them a continuously fed web, coöoperating means, carried by said cylinders for creasing or perforating said web at intervals, means for applying suction to portions of said web alternately whereby alternate portions are drawn first to one cylinder and then to the other to produce folds, and stripping means associated with each cylinder and adapted to act upon one side of the web during the latter part of the time that the suction means of the other cylinder is acting upon the opposite side of said web.

3. A machine of the class described having in combination two stationary chambered bearing members arranged side by side and provided with peripheral channels connected with the interior thereof, creasing or perforating means, a pair of revoluble cylinders by which said means are carried, said cylinders being provided with rows of ports which register alternately with the channels whereby a web received between said cylinders is folded first in one direction and then in the other, and means associated with each cylinder for stripping off the folds and laying them in zigzag form, such means corresponding in number to the number of rows of suction ports.

4. A machine of the class described having in combination a pair of revoluble cylinders adapted to receive between them a

- 5 continuously fed web, coöperating means carried by said cylinders for creasing or perforating said web at predetermined intervals, means for holding alternate portions of said web first upon one cylinder and then upon the other during part of the revolution of said cylinders whereby folds extending in opposite directions are produced, and mechanical means carried by said cylinders for stripping the folds therefrom.
- 10 5. A machine of the class described having in combination a pair of revoluble cylinders adapted to receive between them a continuously fed web, coöperating means carried by said cylinders for creasing or perforating said web at predetermined intervals, suction means for holding alternate portions of said web first upon one cylinder and then upon the other during part of the
- 15 20 revolution of said cylinders whereby folds extending in opposite directions are produced, and mechanical means carried by said cylinders for stripping the folds therefrom.
- 25 6. A machine of the class described having in combination a pair of revoluble cylinders adapted to receive between them a continuously fed web, suction means operated through openings in the peripheries of said cylinders adapted to seize portions of the web and carry them alternately in

opposite directions, and creasing or perforating means mounted in said cylinders in close proximity to said openings and arranged to act approximately simultaneously with the beginning of the operation of the suction seizing means and at approximately the same place on the web.

7. A machine of the class described having in combination a pair of revoluble cylinders adapted to receive between them a continuously fed web, coöperating means carried by said cylinders for creasing or perforating said web at predetermined intervals, and means for holding alternate portions of said web first upon one cylinder and then upon the other during part of the revolution of said cylinders whereby folds extending in opposite directions are produced, said creasing or perforating means being constructed and arranged to act approximately simultaneously with the beginning of the operation of the holding means and at approximately the same place on the web.

In testimony whereof I have signed my name to this specification in the presence of two subscribing witnesses.

FRANCIS MEISEL.
